CLAIM

The ornamental design for a sausage/meat ball tray, as shown and described.

DESCRIPTION

FIG. 1 is a top, front, right side perspective view of a sausage/meat ball tray according to a first embodiment of our new design;

FIG. 2 is a bottom perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof; and,

FIG. 9 is a perspective view of a plurality of trays each covered with clear film and stacked on a front side for display.
